UNITED STATES PATENT OFFICE.

BERNARD S. STONE, OF VANCOUVER, BRITISH COLUMBIA, CANADA.

VALVE.

1,117,924.

Specification of Letters Patent. Patented Nov. 17, 1914.

Application filed September 9, 1913. Serial No. 783,887.

To all whom it may concern:

Be it known that I, BERNARD S. STONE, a citizen of Canada, residing at Vancouver, in the Province of British Columbia and 5 Dominion of Canada, have invented new and useful Improvements in Valves, of which the following is a specification.

The invention relates to a valve designed particularly for use in automobile engines, 10 and constructed to include a section designed for coöperation with the seat and constructed of cast iron, the use of which materially insures the prolonged effective life of the valve without regrinding.

15 The main object of the present invention is the provision of a valve in which the respective sections are assembled and constructed in a manner to permit the use of the cast iron valve section without placing said 20 section under strain in its application in the valve structure, as under such strain the section would be liable to crack when it became heated.

25 The invention in its preferred form of details will be described in the following specification, reference being had particularly to the accompanying drawings, in which:— Figure 1 is a perspective view of the improved valve. Fig. 2 is a vertical central 30 section through same.

Referring particularly to the accompanying drawings, the improved valve is made up to include three distinct parts, a main section 1, a valve section 2, and a clamping section 3.

35 The main section comprises a head 4 of circular outline in plan and convexed upper surface as shown, from which head section centrally depends a circular projection 5 exteriorly threaded, preferably with threads 40 of fine pitch. From the section 5 centrally depends an elongated reduced extension 6 forming a stem of the valve and preferably provided near its lower end with a diametric opening 7 to receive a cotter pin for supporting the lower end of the usual reseating spring.

45 The valve section comprises a cast iron member 8 of annular form and interiorly threaded to coöperate with the threaded projection 5, the exterior or outer edge of the valve section being formed with a valve surface 9 to coöperate with the valve seat. The clamping section comprises an annular 50 member adapted to be forced on to a shank

and to underlie and bear against the valve section, the outer edge 10 of the clamping section being of such form as to arrange said surface wholly within the plane of curvature of the valve face 9 of the section 2.

60 The sections 1 and 3 are preferably of steel, while the valve section 2 is of cast iron. Through the use of this material, the valve surface will not become pitted as repeatedly as if steel were used, so that the valve will 65 not require regrinding as frequently as under other conditions. To provide for manually turning the valve when necessary for clearing the surface I form centrally in the head 4 a diametric kerf 11 in which a screw 70 driver or other appropriate tool may be inserted for the convenient turning of the valve.

75 It is one of the important objects of the present invention to so apply the cast iron section in the valve structure that no strain whatever will be put upon said section during application, and for this reason it is threaded in place through a comparatively fine thread connection. Therefore as such 80 section is without strain, there will be no liability of its cracking under its necessary heating in use.

85 What is claimed is:—

A valve including a main section comprising 90 a head having a convex upper surface to present an extremely narrow peripheral edge, a diametrically reduced exteriorly threaded projection depending centrally from the head, and a stem depending centrally from said projection, a cast iron valve section formed with a threaded opening to coöperate with said threaded projection, said valve section having an exterior diameter uniformly decreased from the upper to 95 the lower surface, the diameter of the upper surface being coincident with the maximum diameter of the head, and a clamping section frictionally engaging the stem and bearing against the threaded projection and valve section, the maximum diameter of the clamping section being coincident with the minimum external diameter of the valve section.

100 In testimony whereof I affix my signature 105 in presence of two witnesses.

BERNARD S. STONE.
